DEVICE FOR GUIDING THE MOVEMENT OF THE RING RAIL IN SPINNING MACHINES

Luigi Vella, Province of Brescia, Cogozzo Valtrompia, Italy

Filed Apr. 21, 1958, Ser. No. 729,963

Claims priority, application Italy May 7, 1957

1 Claim. (Cl. 57—137)

It is an object of the present invention to provide a device for guiding the movement of the ring rail in spinning machines, for the purpose of enabling the use of rings of greater diameter and of increasing the production of the machine. It further makes it possible to reduce the power required for the operation of the machine and, therefore, to attain a sensible saving of absorbed energy.

In ring spinning frames, the ring rail has imparted thereto a reciprocating movement for the formation of the super-imposed layers of yarn and a progressive movement for the formation of the bodies of the cops; said movements being imparted to it by members of the spinning frame which ordinarily are called "lifter rods" and are placed between two contiguous spindles at determined intervals along the machine and cooperate with other members placed on the spinning frame which determine those movements.

The modern trend towards shortening as much as possible the cycles of operation and reducing idle times, in order to attain reduction of working costs, has determined as a consequence a continuous increase of the units of capacity and also with spinning frames the present trend is to obtain larger and larger cops, that is, with greater weight of wound yarn.

Especially with old spinning frames that need is felt most since the capacities attainable with primitive machines are far below present-day requirements, when attempts are made to modifying those spinning frames so as to adapt them to the newest trends.

Although the constructive dimensions of the lifter rod and members connected therewith are reduced to a minimum, said members still constitute a hindrance and a limitation to maximum utilization of the space existing between spindle and spindle, because if one wants to increase the diameter of the rings and, consequently, the diameter of the bobbins obtainable, at the points where the lifter rods are placed, these would rub against the walls of the bobbins thereby causing damage and defects to the wound yarn.

It is an object of the present invention to provide a device enabling the utilization of the space available between the spindles, by means of the displacement of the lifter rod, of its guide and of the members for fastening the ring rail, out of the zone of the spindles, where they do not form any hindrance.

In this case, however, the load upon the lifter rod does not act along the longitudinal axis thereof but always acts vertically to create a moment with respect thereto, because the load is offset.

With conventional systems wherein the lifter rod slides in a guide bush, the offset load would involve an increase of the value of the friction generated by movement, which values prevent practical and economical embodiments of the system.

On the contrary, the instant device overcomes that hindrance, because the lateral thrusts upon the lifter rod as caused by the offset load are carried by the guide

2

through bodies rolling between the surfaces that slide, thereby diminishing the value of passive resistances and, therefore, of the power absorbed by the spinning frame.

Moreover, the reduction of passive resistance affords the possibility of more accurate balancing of the masses moving by reciprocating movement.

The invention will be hereinafter described more in detail with reference to the accompanying drawings which illustrate by way of example an embodiment of the invention as follows:

Fig. 1 shows a longitudinal section of the device and its position with respect to some members of the spinning frame;

Fig. 2 shows a cross-section of the device near the top; and

Fig. 3 shows a front view of part of the spinning frame with the position of assembling of the device.

In the drawings, thin lines represent only those parts of a spinning frame which are indispensable to make clear the operation of the instant device.

On the spindle rail 1 of the spinning frame on which the spindles 2 are placed, there are fixed supports 3 arranged along the spinning frame and each support 3 has a central hole 4 passing along the longitudinal axis of said support: at the two ends of the support and diametrically opposed with respect to the hole there are provided grooves 5 of limited length; within said grooves 5 there are accommodated the balls 6.

In the hole 4 there is placed the lifter rod 7 wherein there are provided the grooves 8 which are diametrically opposed and which run over the whole length of the lifter rod.

At the upper end of the lifter rod 7 there is fixed a bracket 9 on which is placed the ring rail 10 which carries rigid thereto the rings 11 while the lower end of the lifter rod 7 carries a small socket 12 which cooperates with the mobile member 13 of the spinning frame and receives its movement therefrom.

Two small covers 14 placed at the ends of the support 3 serve as closure and limitation to the race of the balls.

Operation of the device is as follows:

On the spindle rail 1 there are fixed the spindles 2 whereon there are fitted empty tubes whereon then the yarn is wound up in superimposed conical layers, the spindles are made to turn, in a manner known per se, by a belt (not shown); the rail 10 carrying the rings 11 and rigid with the lifter rod 7 through the support 9, is driven by the member of the spinning frame 13 cooperating with the support 12 to effect a short reciprocating movement for the formation of the individual layers on the cops and an ascending progressive movement for the formation of the bodies of the cops.

Obviously said movements are carried out by the lifter rod 7 which represents the means for transmission of the movement of the member 13 to the rings 11.

Hence said lifter rod 7 slides while resting on the balls 6 (owing to the off-set load) which in turn roll along the grooves 5 wherein they are contained, and displace to reciprocate for a path shorter than the length of said grooves, while the movement for forming the conical layers is effected.

However at every conical layer the lifter rod 7 (and all the members fixed thereto) undergoes also a progressive upward displacement by some tenths of millimetre each time, whence at a certain time, when the reciprocating displacement is at its upper dead point, the balls 6 will find themselves respectively at contact with the small cover 14 for the upper most ball and with the end of the groove for the lowermost ball.

Hence at that time, a slight sliding will occur between the rod 7 and the balls 6, favoured by the fact that the specific pressure exerted by the rod against the balls

is very small and there is sufficient play between the two members to allow therefor.

Subsequently the reciprocating movement reverses, the rod descends again by a length of path equal to one stroke while resting on the balls which again roll downwards with a displacement proportional to the amount of the stroke, then the movement is reversed and return is made upwards and so on until the tubes fitted on the spindles 2 are completely loaded with yarn.

At that time, by means of conventional operations on the spinning frame, all of the members are brought back to their position of doffing start as in Fig. 1, to begin then again with a new cycle.

Of course what has been hereinbefore described and illustrated may be modified in its details of embodiment in practice within the scope of the invention.

I claim:

In a spinning machine including a ring rail, lifting and guiding means for said ring rail lying in a plane displaced from the plane of the center of gravity of said ring rail, said means comprising a vertical support, a vertical bore through said support, a lifter rod slidably mounted in said bore, said lifter rod being provided with diametrically positioned longitudinal grooves, a first groove in said bore near the upper end thereof on the 25

side of said bore toward the center of gravity of said ring rail and of approximately half the length of the distance of vertical movement of said lifter rod, a ball bearing seated in said first groove in said bore extending into and bearing in one of said grooves in said lifter rod, a second groove in said bore on the side of said bore remote from the center of gravity of said ring rail near the lower end thereof of approximately half the length of the distance of vertical movement of said lifter rod, 10 said second groove being on the diametrically opposite side of said bore from said first groove, a ball bearing seated in said second groove and bearing in the other of said grooves in said lifter bar, and said first groove and said second groove lying in a plane normal to the plane 15 of the center of gravity of the said ring rail.
